FLOTATION APPARATUS

Donald H. Fairchild, Salt Lake City, Utah, assignor of one-half to J. Patton Neeley, E. L. Patten, and Hugh B. Sprague

Application July 17, 1930, Serial No. 468,668

17 Claims. (Cl. 261—93)

This invention relates to improvements in apparatus for carrying out the flotation process for the separation and recovery of the valuable mineral constituents of ores from the gangue minerals or undesirable portions, or for any other commercial processes in which such equipment would be useful.

Another object of the invention is to provide a new and improved type or character of aeration for flotation process purposes particularly.

Other objects of the invention will appear as the following description of a preferred and practical embodiment of the apparatus, and disclosure of the novel process, proceeds.

15 In the drawings which accompany and form a part of the specification of my invention;

Figure 1 is a vertical side section through apparatus embodying the principles of the invention;

20 Figure 2 is a transverse vertical section taken along the line 2—2 of Figure 1;

Figure 3 is a side view, partly in elevation and partly in section through the aerating element and its connection with the source of air under pressure;

25 Figure 4 is a section taken along the line 4—4 of Figure 3;

Figure 5 is a detail showing the interdigitating relation of the distributor head and tubular portions of the aerator when a one-bolt connection is used;

30 Figure 6 is a section taken along the line 6—6 of Figure 3;

Figure 7 is a perspective view of one of the 35 lifter bars.

Before advertiring in detail to the several figures, it may be explained that the flotation process for the separation of the valuable minerals from the undesirable portion of ores relies upon the formation of a froth that may be created by various means, in which froth the particles of the desirable components of the ore are found and which froth, being continuously added to from below, due to some form of aeration or agitation, overflows into suitable launders by which it is delivered to other apparatus for further treatment if such is required. The froth is usually termed "concentrates", the waste portion "tailings" and the mixture of gangue and minerals when ground and mixed with water, etc., is referred to as the "pulp".

The present invention involves improvements in the means used for aerating the pulp and creating the froth and in the manner of aeration.

Now, referring in detail to the several figures, the numeral 1 represents the cell, tank or receptacle to which the pulp is introduced through a suitable feed entrance 2. The aerator, which in general is designated by the reference character 3 is preferably mounted on a substantially horizontal axis near the bottom of the tank or cell 1, the adjacent walls 4 of said tank or cell preferably converging so as to bring portions of the pulp that settle into close proximity to the aerator. One or more launders 5 may be provided at the sides of the tank or cell into which the froth may overflow, said launders inclining if desirable to deliver the froth to a suitable discharge place 6 by gravity from which place it may be conveyed to a settling tank or any apparatus for further treatment. The tank or cell 1 is provided with a discharge overflow 7 for carrying off the pulp from one cell and delivering it to another or to waste or in any other manner disposing of it as desired.

Figure 1 shows that the aerator comprises a hollow shaft 8, shown in better detail in Figure 3 and preferably supported in suitable bearings 9. Said shaft may be rotated by any suitable means, the belt and pulley 10 being suggestive of one means of rotation. The shaft passes through opposite end walls of the tank or cell 1 by way of stuffing boxes 11 which may be of usual or any suitable construction.

The shaft 8 is preferably capped or otherwise closed at its ends and provided outside of the tank or cell 1 with a slip-joint air connection comprising a chambered sleeve 13 surrounding a perforated zone 14 of said shaft, said sleeve being so constructed as to minimize leakage of air to the atmosphere. The sleeve 13 is in communication with a source of air or other desired fluid or vapor under pressure. The hollow shaft 8 communicates with a distributor head 15 and the latter in turn is in communication with a plurality of substantially parallel cylinders or pipes 16 which rotate with said distributor head about the axis of the shaft 8 when the latter is rotated, the cylinders or pipes moving in an orbit about the axis of the shaft 8. The opposite ends of the cylinders or pipes 16 are shown as anchored in a similar distributor head 17 although it is not necessary to always provide the distributor head 17, since any other suitable means for properly supporting the far ends of the pipes 16 will answer the purpose of the invention unless it should be desired to admit air or other fluid under pressure from that end also.

The cylinders or pipes 16 are preferably provided with perforations 18 allowing for the emission of air and said pipes are preferably covered with a foraminous or finely perforated material in order to uniformly distribute the discharging air and sub-divide it into minute bubbles.

Figure 4 shows that two or more foraminous or perforated pipe or cylinder covers may be used, the inner covering 19 being usually for spacing purposes and, in this case, of coarse mesh wire cloth commonly referred to as "hardware cloth" while the outer covering may be of fabric such as twill or filter cloth or of perforated rubber or any other medium suitable to the requirements.

An aerator of this type is more efficient than a mere cylindrical aerator, since in the operation of the latter the air is emitted radially from all sides of the aerator. In the present invention the total surface area of the aerating elements may be substantially increased for a given diameter of the aerator if desired by the use of maximum diameter pipes, but in any case the air is simultaneously emitted in four different directions in that region of the aerator along its longitudinal axis of rotation, thus more completely aerating the body of liquid or pulp that may be in said longitudinal central region. The vital difference may be said to lie chiefly in the fact that with the cylindrical type of aerator the aeration or agitation occurs outside the path of revolution of the cylinder while with the present improvement it is partially intraorbital with respect to the paths of revolution of the several aerating elements.

The cylindrical elements or pipes 16 may be preferably screwed into flanges 21 which in turn are bolted to the distributor heads 15 and 17, the latter having openings which align with the openings in the pipes 16 and connect said pipes

with the aim to cover the whole range of the values of the distribution in each hemisphere and to sample also a sufficient number of stations in each of the four seasons. The following table gives an idea of the stations sampled.

A single boot like this refers to the toe section of the boot. It is made of leather and has a leather sole.

responding excess of force in the horizontal direction of figure 6-21. This is a very large force.

10. **Procesos de creación y desarrollo de la conciencia social.** Se divide en:
 a) Procesos de creación y desarrollo de la conciencia social.
 b) Procesos de creación y desarrollo de la conciencia social.

Philippe le Bel et le pape Urbain V. L'ordre des Templiers fut démantelé en 1312, et le pape Clément V, qui fut le premier à résider à Avignon, fut l'instigateur de la mort de Jeanne d'Arc.

Between 1900 and 1910, the number of immigrants to the United States increased from 1.5 million to 2.5 million.

It is also of interest to note that the following factors are important in determining the magnitude of the difference between these distributions:

ing heads 15 and 17 and suitably secured there-to or to other suitable parts of the aerating unit. The lifter bars 26 of course, rotate with the aerating unit and dip into the heavier por-tion of the pulp that has a tendency to settle in the bottom of the tank or cell 1 lifting such settled or settling material to some point above the aerating element and pouring or dropping said material upon and/or in between the aerat-ing pipes 16 where it is acted upon with optim-um thoroughness by the air bubbles intersect-ing the region adjacent the axis of the assem-bled aerator into an intra-orbital manner.

The froth which results from the aeration of the pulp in the tank or cell 1 collects at the surface of the pulp and overflows into the launders due to the continuous accumulation from below of more froth as the aerating process continues.

While I have in the above description disclosed what I believe to be a practical concept of my invention, it is to be understood that the details as shown or described are merely by way of example and not to be considered as limitative in their relation to the scope of the invention as claimed.

What I claim is:

1. In flotation apparatus including a receptacle, aerating members for discharging air or gas or other fluid or fluids into the pulp within said receptacle near the bottom thereof revolving about a common horizontal axis in such an orbital manner that aeration and/or agitation of the pulp is carried on in the region along the axis of the orbital path of the aerating members. 35

2. Flotation apparatus including a receptacle, means for establishing an aeration zone in said receptacle, intersected by differentially moving groups of upwardly travelling fine air or gas bubble chains, and means for discharging pulp 40 into the region thus aerated.

4. All processes for data collection are separate from the analysis of the resulting measures and will be carried out by different teams. The resulting data are treated as separate, established data to which no further changes will be made. The analysis is carried out by a separate team.

anterior to the dorsal aorta and posterior to the midgut. It consists of a mid-dorsal afferent nerve, a mid-ventral efferent nerve, and a mid-dorsal efferent nerve. The mid-dorsal afferent nerve originates in the mid-dorsal afferent ganglion and passes posteriorly to the mid-dorsal afferent nerve. The mid-ventral efferent nerve originates in the mid-ventral efferent ganglion and passes anteriorly to the mid-ventral efferent nerve. The mid-dorsal efferent nerve originates in the mid-dorsal efferent ganglion and passes posteriorly to the mid-dorsal efferent nerve.

se salutare radio a phalero constitutively, which is the best way to get the goods to the people.

zone traversed by groups of rising bubbles from said conduits.

7. Flotation apparatus as claimed in claim 6, the aerator including stirring means for elevating pulp from beneath said aerator and pouring it into the aerated intra-orbital zone established by the revolution of said conduits.

8. In flotation apparatus including a receptacle, an aerator arranged substantially horizontally in said receptacle near the bottom thereof comprising a hollow shaft for admitting air or gas to said aerator, a plurality of aerating conduits in communication with said shaft and revoluble therewith, and pervious coverings surrounding said conduits for sub-dividing the air or gas jets discharging from said conduits.

9. In flotation apparatus as claimed in claim 8, means for elevating mineral pulp from adjacent the bottom of said receptacle and discharging it into the aerated zone established by said revoluble conduits.

10. In flotation apparatus including a receptacle, an aerator arranged substantially horizontally in said receptacle near the bottom thereof comprising a hollow shaft for admitting air or gas to said aerator, a distributing head with which said hollow shaft communicates, and a plurality of aerating conduits revoluble with said distributing head about the axis of said shaft and communicating with said distributing head.

11. In flotation apparatus as claimed in claim 10, means movable with said aerator for elevating pulp from the bottom of said receptacle and pouring it through the aerated zone established by the revolution of said aerating conduits.

12. In flotation apparatus including a receptacle, an aerator arranged substantially horizontally in said receptacle near the bottom thereof comprising a hollow shaft for admitting air or gas to said aerator, a distributing head having an open ended chamber, a plate detachably closing the open end of said chamber, and a plurality of aerating conduits connected to said plate and communicating with said chamber, and revoluble with said distributing head about the axis of said shaft.

13. Flotation apparatus as claimed in claim 12 including stirrers carried by said aerator and

extending longitudinally of the aerating conduits for lifting mineral pulp from adjacent the bottom of said receptacle and pouring it into the aerated zone established by the revolution of said aerating conduits.

14. Flotation apparatus as claimed in claim 8 including pervious sheets encasing conduits for subdividing the air or gas jets discharging from said conduits.

15. In an apparatus for the concentration of 10 ores or the like by froth flotation, a rotor comprising a plurality of hollow aerating members 15 symmetrically and horizontally positioned in proximity to the bottom of the apparatus, each of said members being provided with a porous medium for the dissemination of a multiplicity of minute air bubbles throughout a body of pulp confined within the apparatus, and means in association with the rotor for rotating it about a substantially horizontal axis common to the 20 members.

16. In an apparatus for the concentration of 25 ores or the like by froth flotation, a rotor comprising a plurality of hollow aerating members 30 symmetrically and, horizontally positioned in proximity to the bottom of the apparatus, each of said members being provided with a porous medium for the dissemination of a multiplicity of minute air bubbles throughout a body of pulp confined within the apparatus, and means in association with the rotor for rotating it about a substantially horizontal axis common to the members, said members communicating with a single air distributing chamber.

17. An apparatus for the concentration of 35 ores, comprising a flotation cell for the retention of a body of mineral pulp undergoing treatment, an inlet for the introduction of pulp to the cell, an outlet for the withdrawal of treated pulp from the cell, and a plurality of parallelly 40 spaced and horizontally disposed aerating members located at or near the bottom of the cell adapted to release finely disseminated air into a body of pulp confined within the cell said members being mounted and provided with 45 means for moving them about a substantially horizontal axis.

DONALD H. FAIRCHILD.
